UNITED STATES PATENT OFFICE.

FRANK V. MILLER, OF SAN FRANCISCO, CALIFORNIA.

CLOSET VALVE.

Application filed August 9, 1922, Serial No. 580,590. Renewed April 27, 1925.

To all whom it may concern:

Be it known that I, FRANK V. MILLER, a citizen of the United States, residing at San Francisco, in the county of San Francisco and State of California, have invented new and useful Improvements in Closet Valves, of which the following is a specification.

The present invention relates to improvements in valves for flush tanks such as are used in connection with toilets, urinals and like bath or toilet fixtures.

The primary object is to provide novel valve mechanism of the character described which will be comparatively simple as to construction, inexpensive, easy to install and capable of being operated in a more reliable and economical manner than types of valve mechanisms such as are now generally employed, it being possible to readily assemble and disassemble the valve mechanism of my invention for the purpose of repair or rearrangement of the parts, without necessitating a complete dismantling of the mechanism.

Another object of the invention is to provide valve mechanism of the character described which will operate to permit an adequate amount of water to flow from the tank without an excessive and wasteful flow such as is usually the case with the ordinary flush valve where the fresh supply of water feeding to the tank flows out before the discharge valve closes.

Another object is to provide valve mechanism of the character described which may be readily and easily adjusted to regulate the amount of water to be discharged upon each flushing operation and which may be readily attached to tanks regardless of the point of introduction of water supply without necessitating changing of the construction of the mechanism.

The invention further contemplates generally improving and simplifying the construction and operation of flush tank valve mechanisms so as to render them more efficient, capable of longer service, easier installation and subject to easier repair.

The invention possesses other advantages and features some of which, with the foregoing will be set forth at length in the following description where I shall outline in full that form of the invention which I have selected for illustration in the drawings accompanying and forming a part of the present specification. In said drawings I have

shown one form of the construction of my invention, but it is to be understood that I do not limit myself to such form since the invention as expressed in the claims may be embodied in a plurality of forms.

Referring to the drawings:

Fig. 1 represents a view of the flush tank with the front side thereof removed showing the mechanism of my invention in front elevation.

Fig. 2 represents a sectional view through the tank at right angles to Fig. 1, showing the mechanism in side elevation.

Fig. 3 represents a detail side elevation of the mechanism showing the manner of adjusting the mechanism to regulate the amount of water to be discharged from the tank.

Referring particularly to the drawings in which one practical embodiment of the invention is shown in detail, 1 designates a flush tank of the type usually employed in connection with urinals and closets, wherein there is provided a discharge member 2 at the lower side and a water supply pipe 3 at the upper rear side. The mechanism of my invention is connected with a valved fitting generally designated 4, in turn connected with the supply or intake pipe 3. An operating handle 5 for operating the valve of the fitting 4 is located within the tank so as to be accessible from the upper open side thereof. Connected with the fitting 4 is a T fitting 6, in the lower end of which a valve 7 is mounted so as to control the flow of water out through the extension 8 of said fitting. The extension 8 has screwed into its upper end a T coupling 9, to the upper end of which, through a reduction coupling 10, is connected an auxiliary supply pipe 11, which is horizontally extended. The lower end of the coupling 9 has a pipe 9' connected therewith and said pipe extends downwardly to a point near the bottom of the tank whereby a noiseless water feed into the tank is provided.

The discharge member 2 is closed by a valve 12 having a central opening 13 therefor, as is customary in such discharge valves. Extending upwardly from the valve in communication with the opening 13 is a tubular stem 14, the upper end of which is connected with the valve operating mechanism of the invention as will be later described. The auxiliary pipe 11 is arranged so as to discharge water into the upper open end

of the tubular stem 14 so that said water will run into the bowl, not shown, and maintain a quantity of water in the top of the bowl after a flushing operation. Bifurcated extensions 15 are provided on opposite sides of the valve and engage upright guide rods 16 which are carried on the fitting 2 and extend upwardly to form support for parts of the operating mechanism, as will be later described.

The operating mechanism comprises the customary ball float 17 which is mounted upon one end of a lever 18 and arranged to be lifted and lowered by action of the water in the tank. At a point intermediate of its ends a lever is pivoted as at 19 to a link 20, which is in turn pivoted as at 21 to one end of a valve stem operating lever 22. The lever 22 extends through a slot 23 in the stem 24 of the valve 7 and at its other end is pivoted as at 25 to a similar rigid extension 26 carried by the fitting 6. On the other side of the fitting 6 is a downwardly bifurcated extension 27, in the bifurcation of which a lever 22 operates and to the lower end of which the adjacent end of the lever 18 is pivoted as at 28. The pivots 19, 21, 25 and 28 include L-shaped screw members 29 which are removable to permit of ready assembling and disassembling of the mechanism.

It will thus be seen that upon up movement of the float 17 and rod 18, as when the tank is being filled with water, the link 20 will push upwardly on the lever 22, which latter in turn pushes the stem 24 upwardly and closes the valve 7. When the valve 12 is opened the float 17 lowers the lever 18 and other connections pulling the valve 7 into open position and allowing a supply.

The means for operating the discharge valve 12 comprises an operating handle 30 which is located on the outside of and in front of the tank 1. A shaft 31 which extends through an opening 32 in the front wall of the tank is rotatably mounted in one of the guide posts or standards 16, said shaft being held in place by a cotter pin 33. Fixed to the shaft 31 is a crank arm 34 to the outer end of which is pivoted a locking link 35 which slidably extends through a keeper member 36 fastened to the other guide 16. The link 35 is provided with a notch 37 adjacent to its other end, which notch is adapted to receive one end of the keeper 36 so as to hold the link in up position as will be later described. A short link 38 is connected with the link 35 and crank arm 34 at the point of connection of the latter and depends from the crank arm. A flexible element 39 is connected with the lower end of the link 38 and with the upper end of the valve stem 14. When the operating handle is depressed the crank arm 34 will, through the link and

flexible element, lift the valve stem 14 and open the valve 12, lifting upwardly on the locking link 35 and causing the lower end of the keeper 36 to engage in the notch 37, whereupon the mechanism will be held in such position as to hold the valve 12 open. Attached to the lower end of the link 35 is a weight member 40 which operates to cause a positive engagement of the member 36 in the notch 37. As a means for dropping the lever 35 and causing the notch to be moved clear of the member 36 so that the valve 12 may close, there is provided a link 41 which is pivoted as at 42 to the lower portion of the link 35 and which is pivoted as at 43 to one end of a lever 44. The lever 44 is pivoted as at 45 intermediate of its ends to a depending member 46 supported by a rod 47 which rod connects the upper ends of the guide rod 16. The lever 44 at its ends carries a depending flexible element 48 preferably in the nature of a chain, one link of which, adjacent its lower end as shown at 49, is slidably mounted upon the lever or rod 18.

Assuming that the tank is filled with water to the level shown in Figs. 1 and 2, when the handle 30 is depressed, the valve 12 will be lifted and water will discharge from the tank, the locking link 35 will be held by the notch 37 engaging the member 36 in position to maintain the valve in open position. However, when the slack of the flexible element or chain 48 is taken up upon the lowering of the ball float and rod 18, such action taking place when the tank has discharged its contents through the outlet 2, the lever 44 will be rocked and communicate a pull on the link 35 through the link 41. This will move the notch 37 clear of the member 36 and permit the parts to return to normal position assisted by the action of the weight 40. As soon as the locking link 35 is released the valve will gravitate into closed position and the closing of the valve is co-incident with the opening of the valve 7 and the feed of a fresh supply of water to the tank. The tube 14 acts as an overflow pipe.

By adjusting the flexible element 48 on the rod 18 the trip action may be regulated so as to cause the discharge valve to close at different times whereby regulation of the amount of water to be discharged may be effected.

I claim:

1. In a valve mechanism for flush tanks the combination with a tank having a discharge opening and an intake, of a valve controlling the discharge opening, a valve controlling the intake, means operating automatically when the water level in the tank reaches a pre-determined point for closing the intake valve and for opening said valve when the water lowers, an operating mem- 130

ber on the tank means of connection between said operating member and the discharge valve providing for opening of the discharge valve upon movement of the operating member, a notched member connected with said last-named means a member adapted to extend into said notch upon opening of the discharge valve whereby said notch member will hold the discharge valve in open position, means operated by movement of intake valve operating means for moving said notched member out of position holding the discharge valve open and a weight depending from one end of said notched member.

2. In valve mechanism for flush tanks the combination of a tank having a discharge opening and an intake, of a valve controlling the intake, means operated automatically when the water in the tank reaches a pre-determined level for closing said valve and opening the valve when the water recedes below said level, a valve controlling the discharge opening, an operating member movable upon the tank, means of connection between the discharge valve and operating member providing for opening of the discharge valve upon movement of the operating member, means for automatically locking the discharge valve in open position upon opening of said valve, comprising a member having connection with said means of connection, a stationary member, said first named member having a notch therein adapted to receive the stationary member means operating to release said locking

means upon movement of the intake valve operating means to a pre-determined point, which last-named means includes a lever connected with the notched member, a support for the lever and a flexible element connected with said lever and said intake-valve operating means. 40

3. In valve mechanism for flush tanks the combination with a tank having a discharge opening and an intake, of a valve controlling the discharge opening, a valve controlling the intake, means operating automatically when the water level in the tank reaches a pre-determined point for closing the intake valve and for opening said valve when the water lowers, an operating member on the tank, means of connection between said operating member and the discharge valve providing for opening of the discharge valve upon movement of the operating member, a notched member connected with said last-named means, a member adapted to extend into said notch upon opening of the discharge valve whereby said notched member will hold the discharge valve in open position and means operated by movement of the intake valve operating means for moving said notched member out of position holding the discharge valve open, which means comprises a support, a lever pivoted on the support, a link connection between the lever and said notched member and a flexible element connected with said lever and adjustably connected with the intake valve operating means. 50 55 60 65 70

FRANK V. MILLER.
